(57) **CLAIM**

The ornamental design for an electric oven, as shown and described.

DESCRIPTION

FIG. 1 is a front perspective view of an electric oven, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 2; and,

FIG. 12 is an enlarged detail view of area 12 in FIG. 2.

The broken lines in the drawings illustrate the portions of the electric oven, which form no part of the claimed design.

The dash-dot-dash broken lines illustrate the border of the enlarged detail views and form no part of the claimed design.

1 Claim, 12 Drawing Sheets
